UNITED STATES PATENT OFFICE.

LOYD R. STOWE, OF ST. LOUIS, MISSOURI.

HEAT-EXCHANGING MECHANISM.

Application filed February 9, 1924. Serial No. 691,614.

Among the objects of this invention are to provide an economical means of transferring heat from one mass of moving gas to another mass of moving gas; to so arrange the heat exchanging circuit that there will be a very high rate of heat exchange through the heat exchange circuit; to provide mechanical means for moving the two masses of gas between which the heat is exchanged; to combine the gas driving means with the heat exchanger in one piece of apparatus so as to conserve space and materials; to so arrange this apparatus that there will be the minimum number of changes in direction of flow of the gases, thus reducing the amount of power to a minimum which will be required for moving the gases through the apparatus; to produce an improved means for feeding the gas through the apparatus; to produce a mechanism whereby the heat in the space which surrounds the heat producing mechanism and which is ordinarily wasted may be utilized to the fullest extent; to provide in an apparatus of the character described means for removing from the moving gases certain particles of solid materials; to provide means whereby the interior of the apparatus may be cleaned; to improve generally upon apparatus of the character stated; and such further objects, advantages, and capabilities as will hereafter more fully appear, and are inherent in the structure disclosed.

My invention further resides in the combination, construction and arrangement of parts illustrated in the accompanying drawings, and, while I have shown therein a preferred embodiment of my invention, I desire the same to be understood as illustrative only and not as limiting said invention.

In the drawings annexed hereto and forming a part hereof, Fig. 1 is a fragmentary longitudinal sectional elevation of what I now consider a preferred embodiment of my invention; Fig. 2 is a transverse sectional elevation of the apparatus shown in Fig. 1.

Referring to the annexed drawings in which one application of this heat exchanger in connection with steam boilers is illustrated, 1 denotes the heat producing apparatus, 2 designates the pipe by means of which the products of combustion are carried away from the heat producing apparatus and 3

the pipe or pipes by means of which pre-heated air is carried to the space in connection with the firebox, through which air is supplied to the fire to support combustion. 4 is a balcony floor or the like above the heat producing apparatus and through this floor are certain openings for the passage of the pipes 2 and 3 and the passage of air from the space surrounding the heat producing apparatus 1. Upon the floor is mounted a casing 6 comprising a pair of chambers 5 and 6, through a portion of the latter of which extends an annular discharge opening 7 communicating at one end with the chamber 5 and at its opposite end with the smoke stack 8. Passing through the chambers 5 and 6 is a rotating shaft 9 supported at its ends, or wherever most convenient, by standards 10. This shaft is rotated by any suitable connection 11 to any desired motive means 12 such as a motor. Carried by the shaft 9 are two fluid moving means 13 and 14, mounted respectively in the chambers 5 and 6.

The lateral wall 15 of the chamber 5 is frusto-conical in form. The wall of the chamber 5 may be made integral with that of chamber 6 and with pipe 2, if desired, or may be made in readily detachable sections, if preferred. It is at present considered preferable not to have this chamber integral with the other chamber but to have at least certain parts thereof removable for ready access to the fan 13. At the lower side of this casing there is a downwardly extending discharge opening 17 which dips into a fluid contained in receptacle 18. Ordinarily water will be kept in this receptacle to form a water seal for the discharge opening 17. This water will ordinarily prevent any of the gases flowing through the chamber 5 from being forced outwardly through the opening 17, but will permit solid matters accumulating in the chamber 5 to drop downwardly into the pan 18. If these particles should happen to be hot cinders or even live coals, they will be cooled and quenched by the water in the pan 18, thus obviating any danger from this source. Naturally, the pan 18 will be preferably made removable so that any accumulation of solid matter in the pan may be removed. The tendency of the frusto-conical wall 15 is to cause the gases thrown outwardly by the fan 13 to thrust forwardly toward the annular dis-

charge opening 7 and to keep the whole body of gases moving forwardly without the presence of any stagnant portions.

A substantially tight bearing 19 prevents the gases coming from the chamber 1 from following a course along the shaft 9 into the chamber 6, while a similar bearing 20 prevents gases passing along the shaft 9 between the chamber 6 and smoke stack 8. It will be seen by examination of the drawings that the annular discharge opening 7 divides a portion of the chamber 6 into an outer portion through which heated gases are caused to move and an inner portion in which the fan 14 rotates to force these gases outwardly. Access between the inner and outer portions is by means of a large number of small tubular openings of any desired shape but preferably cylindrical, these channels being formed by securing tubes 21 in openings in the walls of the annular discharge opening. A wall 22 divides the chamber 6 into two parts 23 and 24. Heated air from the boiler room will rise and pass through the opening 25 and the opening 26 surrounding the pipe 2 into the chamber above the balcony floor and from this space will be drawn through the openings of the tubes 21 into the space 24. From here the heated air moves forwardly through the portion 23 of the chamber 6 and out through the tubes 21 again into the outer portion of this chamber, then passing through the pipe 3 to the combustion chamber as heretofore explained. It will be observed from the foregoing that the hot gases passing through the pipe 2 enter the annular discharge chamber 7 and are gradually cooled down as they advance therethrough toward the stack 8. Entering warmed air will first pass through the tubes farthest from the pipe 2 which are the cooler tubes and will then pass through the tubes nearer to the pipe 2 thus being heated to their highest temperature, just before being passed into the combustion chamber.

It will be apparent from the foregoing that a large portion of the heat in the gases of combustion which has heretofore been wasted will now be utilized in raising the temperature of the air which is used to support combustion in the furnace. This reduces the amount of heat required to raise this air to the point of combustion, thus saving in the amount of fuel consumed. Also, a large number of small tubes will get a larger proportion of the air in contact with the heated surface than will a smaller number of larger tubes. Because of the fact that the air passing through these tubes is substantially free of material which would soil and clog them, they can be made smaller than they could if gases carrying a large amount of soot were to be passed therethrough. In this way a larger percentage

of the air to be heated is brought into contact with the heat transferring surface. The tubes 21 can be arranged in rows or staggered, as desired, but it is, for some reasons, considered preferable to have them arranged in rows. For example, by having openings in the front end of the apparatus, which openings are covered by removable closure members 28, it will be possible by means of a hand lance or similar dust blowing arrangement, to blow out of the annular discharge opening a large portion of the dust and dirt which may accumulate therein between the tubes 21, the plates or doors 28 being removed for this purpose. If desired, the end carrying the doors 28 may be removable for access to the interior of the structure. Also, the frusto-conical wall 29 may be removably connected in place, the particular means for securing removability being immaterial. There is also provided around the stack 8 an upstanding wall 30 the upper end of which is covered by a member 31 having a downwardly depending flange 32. This will prevent snow, rain, and the like, from entering the opening surrounding the stack 8 but will permit air to come in to supply any air needed during the operation of the apparatus, in excess of the air which enters through the openings 25 and 26. It is believed that the operation of my device will be clear from the foregoing description of what I now consider the preferred form of my construction.

Having now described my invention, I claim:

1. A preheater comprising an annular casing provided with an interior air chamber, means to circulate heated gases through said casing from one end to the other thereof, air ducts extending transversely of the direction of flow of said gases, the ducts adjacent the discharge end of said casing being in communication with the exterior thereof and constructed and arranged to supply air to said chamber, a tapered wall located in said chamber and arranged to deflect the incoming air toward the opposite end of said casing.

2. A preheater comprising an annular casing, said casing being provided with an interior air chamber, means to circulate heated gases through said annular casing from one end toward the other, transverse ducts extending through said annular casing and communicating with said air chamber, a partition separating said ducts into sets and a wall surrounding the outer ends of a portion of said ducts and spaced therefrom to provide a supplemental chamber, ducts leading from said supplemental chamber to convey heated air therefrom.

3. In apparatus of the character indicated, a casing having a plurality of compartments therein, a fuel burning installation,

a duct leading from said installation to one of the compartments, a duct leading from another of said compartments to said installation, an annular discharge outlet from the 5 first compartment extending through said other compartment, and narrow tubular passages extending through the walls of the annular discharge outlet to carry gases through said outlet without commingling with the 10 gases carried thereby.

4. In apparatus of the character indicated, a casing having a plurality of compartments therein, a fuel burning installation, a duct leading from said installation 15 to one of the compartments, a duct leading from another of said compartments to said installation, an annular discharge outlet from the first compartment extending through said other compartment, and narrow 20 tubular passages extending through the walls of the annular discharge outlet to carry gases through said outlet without commingling with the gases carried thereby, the first compartment having a frusto-conical lateral wall, the larger end of which surrounds the said annular discharge outlet. 25

5. In apparatus of the character indicated, a casing having a plurality of compartments therein, a fuel burning installation, a duct leading from said installation to one 30 of the compartments, a duct leading from another of said compartments to said installation, an annular discharge outlet from the first compartment extending through said other compartment, narrow tubular passages extending through the walls of the annular discharge outlet to carry gases through said outlet without commingling with the gases carried thereby, the first compartment having a frusto-conical lateral wall, the larger end of which surrounds the said annular discharge outlet. 35

6. In apparatus of the character indicated, a casing having a plurality of compartments therein, a fuel burning installation, a duct leading from said installation to one 40 of the compartments, a duct leading from another of said compartments to said installation, an annular discharge outlet from the first compartment extending through said other compartment, the first compartment having a frusto-conical lateral wall, the larger end of which surrounds the said annular discharge outlet, and an impeller forcing gases against said frusto-conical wall and through said annular discharge outlet. 45

7. In apparatus of the character indicated, a casing having a plurality of compartments therein, a fuel burning installation, a duct leading from said installation to one of the compartments, a duct leading from another 50 of said compartments to said installation, an annular discharge outlet from the first compartment extending through said other compartment, the first compartment having a frusto-conical lateral wall, the larger end of which surrounds the said annular discharge outlet, and an impeller forcing gases against said frusto-conical wall and through said annular discharge outlet. 55

8. In apparatus of the character indicated, a casing having a plurality of compartments therein, an annular discharge outlet from one compartment extending through another of said compartments, the first compartment having a frusto-conical lateral wall, the larger end of which surrounds the said annular discharge outlet, and an impeller forcing gases against said frusto-conical wall and through said annular discharge outlet. 60

9. In apparatus of the character indicated, a casing having a plurality of compartments therein, an annular discharge outlet from one compartment extending through another of said compartments, the first compartment having a frusto-conical lateral wall, the larger end of which surrounds the said annular discharge outlet, and an impeller forcing gases against said frusto-conical wall and through said annular discharge outlet. 65

10. In apparatus of the character indicated, a casing having a plurality of compartments therein, an annular discharge outlet from one compartment extending through another of said compartments, the first compartment having a frusto-conical lateral wall, the larger end of which surrounds the said annular discharge outlet, and an impeller forcing gases against said frusto-conical wall and through said annular discharge outlet. 70

11. In apparatus of the character indicated, a casing having a plurality of compartments therein, an annular discharge outlet from one compartment extending through another of said compartments, the first compartment having a frusto-conical lateral wall, the larger end of which surrounds the said annular discharge outlet, an impeller forcing gases against said frusto-conical wall and through said annular discharge outlet, a discharge opening extending downwardly from said first compartment, and a fluid containing pan into which said last mentioned opening extends. 75

12. In apparatus of the character indicated, a casing having a plurality of compartments therein, an annular discharge outlet from one compartment extending through another of said compartments and narrow tubular passages extending through the walls of the annular discharge outlet to carry gases through said outlet without commingling with the gases carried thereby, said annular discharge outlet extending beyond the compartments and having, both inside and outside the casing, tubular channels connecting the walls of the said annular discharge outlet. 80

13. In apparatus of the character indicated, a casing having a plurality of compartments therein, an annular discharge outlet from one compartment extending through another of said compartments and beyond the same and having, both inside and outside the casing, tubular channels extending through the walls of the annular discharge outlet and connecting the space outside of the annular discharge outlet with that inside thereof, said channels carrying gases through said outlet without commingling with the gases carried thereby. 85

12. In apparatus of the character indicated, a casing having a plurality of compartments therein, an annular discharge outlet from one compartment extending through the other compartment and beyond the same and having, both inside and outside the casing, tubular channels extending through the walls of the annular discharge outlet and connecting the space outside of the annular discharge outlet with that inside thereof, and impellers located in the two compartments to actuate fluids through the annular discharge outlet and the tubular channels, said fluids passing transversely of each other without commingling.

13. In apparatus of the character indicated, a casing having a plurality of compartments therein, an annular discharge outlet from one compartment extending through the other compartment and beyond the same and having, both inside and outside the casing, tubular channels extending through the walls of the annular discharge outlet and connecting the space outside of the annular discharge outlet with that inside thereof, impellers located in the two compartments to actuate fluids through the annular discharge outlet and the tubular channels, one of the compartments having an opening extending downwardly from its lower portion and a water seal into which said opening dips.

14. In apparatus of the character indicated, a casing having a plurality of compartments therein, an annularly arranged discharge outlet from one compartment extending through the other compartment, the first compartment having a frusto-conical lateral wall, the larger end of which surrounds the said annularly arranged discharge outlet, and an impeller forcing gases against said frusto-conical wall and through said annularly arranged discharge outlet.

15. In apparatus of the character indicated, a casing having a plurality of compartments therein, a discharge outlet from one compartment extending through the other compartment, the first compartment having a frusto-conical lateral wall, the larger end of which surrounds the discharge outlet, and an impeller forcing gases against said frusto-conical wall and through said discharge outlet.

16. In apparatus of the character indicated, a casing having a plurality of compartments therein, an annularly arranged discharge outlet from one compartment extending through the other compartment, tubular passages extending through the discharge outlet or outlets to carry gases there-through without contact between the gases in the tubular passages and those in the dis-

charge outlet, the first compartment having a frusto-conical lateral wall, the larger end of which surrounds the annular discharge outlet, and an impeller forcing gases against said frusto-conical wall and through said annular discharge outlet.

17. In apparatus of the character indicated, a casing having a plurality of compartments therein, an annularly arranged discharge outlet from one compartment extending through the other compartment, tubular passages extending transversely through the discharge outlet to carry gases therethrough without contact between the same, the first compartment having a frusto-conical lateral wall, the larger end of which surrounds the annular discharge outlet, and an impeller forcing gases against said frusto-conical wall and through said annular discharge outlet.

18. A preheater comprising a casing, ducts arranged transversely of said casing, a drive shaft extending into said casing, said shaft being provided with a fan member constructed and arranged to circulate flue gases or the like longitudinally through said casing, a second fan mounted on said shaft and constructed and arranged to circulate air through said transversely arranged ducts.

19. A preheater comprising an annular casing with an air chamber formed interiorly thereof, transverse ducts extending through said annular casing and communicating with said chamber, a drive shaft extending through said air chamber, a fan member carried thereby exteriorly of said chamber arranged to circulate gases through said casing and a fan member mounted on said shaft in said air chamber to circulate air through said ducts.

20. In apparatus of the character indicated, a casing having a plurality of compartments therein, a fuel burning installation, a duct leading from said installation to one of the compartments, a duct leading from another of said compartments to said installation, an annular discharge outlet from the first compartment extending through said other compartment, the first compartment having a frusto-conical lateral wall, the larger end of which surrounds the said annular discharge outlet, a shaft extending through said compartments and carrying an impeller in each of them for forcing gases against said frusto-conical wall and through said annular discharge outlets, respectively.

In witness whereof, I hereunto subscribe my name to this specification.

LOYD R. STOWE.
